Primary Examiner — Khawaja Anwar*Assistant Examiner* — Julice Seung Eun Oum(74) *Attorney, Agent, or Firm* — COOLEY LLP(57) **CLAIM**

The ornamental design for an exercise weight, as shown and described.

DESCRIPTION

FIG. 1 is a perspective view of an embodiment of the exercise weight;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a back view thereof.

The broken lines (e.g., showing discrete portions of the exercise weight) are directed to environment, and form no part of the claimed design. The thin solid lines illustrate surface contour and form no part of the claimed design.

1 Claim, 7 Drawing Sheets(56)
